UNITED STATES PATENT OFFICE.

RICHARD D. GALLAGHER, JR., OF NEW YORK, N. Y.

DRAFT-RIGGING FOR RAILWAY-CARS.

1,231,248.

Specification of Letters Patent. Patented June 26, 1917.

Application filed January 4, 1916. Serial No. 70,199.

To all whom it may concern:
Be it known that I, RICHARD D. GALLAGHER, Jr., a citizen of the United States, residing at New York, in the county and State of New York, have invented certain new and useful Improvements in Draft-Rigging for Railway-Cars; and I do hereby declare the following to be a full, clear, and exact description of the same, reference being had to the accompanying drawings, forming part of this specification.

This invention relates to draft rigging for railway cars, the objects of the invention being to make a structure of maximum efficiency which will occupy a very limited space and which, at the same time, may be assembled on a car at a minimum expense. The improved rigging of the present invention provides for the proper flexibility of movement of the cars with relation to each other in a very compact space without seriously cramping or distorting any of the parts of the rigging, and, by reason of its compactness, the device is particularly adapted for use in cars having no platforms and with little overhang beyond the bolsters, such as ore cars and the like. It will be understood, however, that the features of the invention may be embodied in draft rigging for any type of car, wherein it is desired that a compact rigging of maximum efficiency be employed.

The invention consists in certain novel details of construction and combinations and arrangements of parts as will be herein-after described and pointed out particularly in the appended claims.

In the accompanying drawings,—

Figure 1 is a top plan view of a draft rigging constructed in accordance with the present improvements.

Fig. 2 is a longitudinal section of the same.

Fig. 3 is a front elevation of the rigging.

Fig. 4 is a section on the line 4—4 of Fig. 1.

Fig. 5 is a section on the line 5—5 of Fig. 1.

Fig. 6 is a bottom plan view of the rigging.

Like characters of reference in the several figures indicate the same parts.

In the form shown in the accompanying drawings, the longitudinal center sills A of a car are conveniently formed of channel iron with the usual vertical webs, and are

spaced for the reception between them of the draft rigging of the present invention, the said draft rigging being incorporated between and supported by said sills. It will be understood that the sills A above referred to may be either the sills which extend through the car from end to end, or supplemental sills attached to the through-sills in any preferred manner. The framing of the car, which is connected with the sills A is of any preferred construction and, inasmuch as it forms no part of the present invention, the framing is not shown in the accompanying drawings.

Between the forward extremities of the sills there is mounted what may be for convenience termed the front stop for the front follower plate. In the present instance, this front stop consists of two castings, an upper casting B and a lower casting B'. Both castings are rigidly connected to the sills A, and the castings are spaced apart and of proper formation to receive the shank C of the coupler C. These castings forming the front stop also constitute the abutment for the follower plate D of the draft rigging. The lower casting performs the function of a carry iron for the coupler and its shank. Both castings perform the function of an abutment for resisting draft strains transmitted through the coupler shank to the rear of the casting, and, under excessive buffing stress, and the upper casting may form an ultimate stop for the coupler head when driven inwardly by excessive pressure. Means, however, is provided for dissipating most of the buffing stress or shock before the coupler head can come into engagement with the upper stop casting, as will be hereinafter more fully set forth.

In the preferred construction, the face of the lower casting B' is formed with a flange b which overlies or extends beyond the end of the sills. The upper casting B terminates short of the forward end of the sills A, and its flange b' therefore is located to the rear of the end of said sills. At the forward portion of the upper face of the lower casting, is positioned an intermediate wear plate b².

Between the upper portion of the sills A and positioned forwardly of the flange b' of the upper casting B is a shock absorbing member designed to receive the impact of the coupler head under excessive buffing stress. This shock absorbing member is preferably in the

formed of a metal forging of suitable size and shape, such as a plate D rigidly connected to the sills A. Under heavy buffing stress, the full force of the coupler head C will be brought to bear on the plate D, and in case of the failure of the friction and resilient elements to act, the plate D will be first deflected or crushed, thereby dissipating a large amount of energy before the 10 coupler can injure the castings. The strain under heavy buffing stress is principally on the upper casting B and the plate D thus serves in a large measure to protect it from injury.

15 The shank C' of the coupler C is provided with a transverse opening c (see Fig. 2) in which the transverse pin E fits snugly. This pin extends through openings e in the vertical webs of the sills A, which are 20 of greater length than the dimension of the pin along the longitudinal axis of the rigging to permit forward and rearward movements of the pin in unison with the forward and rearward movements of the coupler shank C', under draft and buffing stresses. On outward movement from normal position, therefore the pin and the coupler shank move outwardly in unison, and on inward movement from normal position, 30 the pin and coupler shank move inwardly in unison.

The normal position of the coupler longitudinally is maintained by the yielding pressure resisting member of the rigging, and 35 this member is located behind the follower plate F which occupies a position to the rear of the vertically alined inner flanges b³ of the castings B, B' and bridges the coupler shank opening in the front castings (Fig. 40 2). Connected with the pin E are the side members g of a draft yoke G. Said draft yoke is preferably composed of a single bar or member, substantially U-shaped and with its forward open end receiving the shank C' and its rear closed end g' passing around the bottom of the pressure resisting member. The forward ends of the side members g of the yoke are provided with elongated slots g² to receive the pin E, and to permit 45 the rearward movement of the pin E in unison with the coupler shank, it being understood that during this rearward movement the draft yoke G remains stationary. Under draft stress the yoke is carried forward 50 by the pin E. The pin E may be secured to its connected parts by providing it with a head e at one end and at the opposite end with a washer and cotter pin e', although any other method of preventing slipping of 55 the pin will be sufficient for the purposes of the present invention.

60 Between the follower plate F and the rear end g' of the draft yoke is the yielding pressure resisting member, which, in the present embodiment is of the type disclosed in my co-

pending application Serial No. 62,551, filed November 20, 1915, having wedge blocks H mounted in a friction box I, supported by the barrel L, the said wedge blocks being located on each side of a center wedge K. The center wedge K is held up with a yielding pressure by the springs L' in barrel L, which springs press the center wedge into engagement with the wedge blocks and also into engagement with a tongue f on the follower plate F. Said wedge blocks are suitably recessed or slotted for the reception of the tongue f of the follower plate, as more fully set forth in my said co-pending application. The wedge blocks H and the center wedge K augment the spring resistance by frictional resistance, a feature common to many patents heretofore granted this applicant. It will be understood that the pressure resisting member operates both under draft and buffing stress, to absorb the strain in a manner well known in the art. Under buffing stress, the strain is transmitted to the friction blocks by the follower plate F, the barrel L remaining stationary and the movement of the blocks is against the yielding resistance of the springs within the barrel. Under draft stress, the follower plate F remains stationary abutting against the vertically alined inner flanges b³ of the front stop castings, whereas, the barrel moves, the strain being taken up by the friction blocks and the springs within the barrel.

Fixed between the sills A and positioned to the rear of the barrel L and the rear end of the draft yoke G is the rear stop casting M. According to the present invention, this stop casting is constructed of such cross section as to impart maximum strain resisting properties to the casting. The casting, which is framed in between the sills A, is provided with a front bumping face m, of somewhat less transverse dimension than the main rear portion of the casting and connected with the rear side vertical webs m' by tapering vertical webs m². The central vertical web m³ extends from the rear of the bumping face m and is reinforced by transverse webs m⁴ which connect the opposite sides of the central vertical web with the side webs m'. The central vertical web m³ is further reinforced by horizontal flanges m⁵ extending along each side of the web and preferably tapering from the rear of the bumping face, into the opposite sides of the web, as shown in Fig. 1. The tapering vertical webs m² are respectively reinforced by inner horizontal flanges m⁶.

The bottom of the spring barrel L is provided with a reinforcing member N, this being a casting or other suitable means for thickening up the bottom of the barrel. To avoid making a heavy section of metal the reinforcing member is provided with open-

ings, *n*. The top and bottom walls of the member *N* are inclined to impart a tapering end to the barrel, as shown in Fig. 2. The function of the member *N* is to reinforce the barrel against deflection, since, in the present construction, the rear stop casting does not bear over the entire bottom of the barrel but through the intermediary of the yoke, and the strains are thus largely within the walls of the barrel.

On the sides of the barrel *L* are lugs *l* which engage the side members *g* of the yoke *G*. These lugs are cast or secured to the barrel, and serve to keep the yoke in proper alignment relatively to the other parts of the rigging.

The yielding resistance member is supported by a carrier *O* running lengthwise beneath the rigging. The forward end of said carrier is bolted to the bottom of the lower front stop casting, as shown at *o*, and the rear end of the carrier to the bottom of the rear stop casting, as at *o'*. The above construction provides a structure of maximum strength and rigidity for the support of the yielding resistance member.

What is claimed is:

1. In a draft rigging for railway cars, the combination with spaced longitudinal car sills, of a coupler shank, a front stop mounted between the sills at their forward ends adapted for the reception of a coupler shank, a follower plate seating against the inner face of said stop, a draft yoke composed of a single member having its forward end open to receive the coupler shank and its rear end closed, a transverse shank engaging pin having a substantially rigid connection with the coupler shank and a loose connection with the draft yoke, whereby the shank and yoke move in unison under draft and the shank moves relatively to the yoke under buffing stress, and a yielding pressure resisting member interposed between the follower plate and the closed rear end of the yoke.

2. In a draft rigging for railway cars, the combination with spaced longitudinal car sills, of a coupler shank, a front stop mounted between the sills at their forward ends, adapted for the reception of the coupler shank, a follower plate seating against the inner face of said front stop, a draft yoke composed of a single member having its forward end open to receive the coupler shank and its rear end closed, a transverse shank engaging pin connecting the coupler shank with the yoke, a yielding pressure resisting member interposed between the follower plate and the closed rear end of the yoke, and means for centering and aligning the yoke relatively to the pressure resisting member.

3. In a draft rigging for railway cars, the combination with spaced longitudinal

car sills, of a coupler shank, a front stop mounted between the sills at their forward ends, adapted for the reception of the coupler shank, a follower plate seating against the inner face of said stop, a draft yoke composed of a single member having its forward end open to receive the coupler shank and its rear end closed, a transverse shank engaging pin connecting the coupler shank with the yoke, a yielding pressure resisting member including a barrel interposed between the follower plate and the closed rear end of the yoke, and lugs carried by the barrel and adapted to engage the sides of the yoke to center the same relatively to the barrel.

4. In a draft rigging for railway cars, the combination with spaced longitudinal car sills, of a coupler shank, upper and lower castings rigidly mounted between and connecting the sills at their forward ends, the front face of the upper casting lying to the rear of the front face of the lower casting, said castings being spaced apart for the reception of the coupler shank, a shock absorbing member located between the sills forwardly of the upper casting, a follower plate seating against the inner face of the castings, a draft yoke connected with the coupler shank, and a yielding pressure resisting member interposed between the follower plate and the rear end of the draft yoke.

5. In a draft rigging for railway cars, the combination with spaced longitudinal car sills, of a coupler shank, upper and lower castings rigidly mounted between and connecting the sills at their forward ends, the front face of the upper casting lying to the rear of the front face of the lower casting, said castings being spaced apart for the reception of the coupler shank, a forging connecting the sills forwardly of the upper casting, and adapted to be engaged by the coupler under excessive buffing strains, a follower plate seating against the inner face of the castings, a draft yoke connected with the coupler shank and a yielding pressure resisting member interposed between the follower plate and the rear end of the draft yoke.

6. In a draft rigging for railway cars, the combination with spaced longitudinal car sills, of a coupler shank, a front stop mounted between the sills at their forward ends, adapted for the reception of the coupler shank, a follower plate seating against the inner face of said front stop, a draft yoke connected with the coupler shank, a yielding pressure resisting member interposed between the follower plate and the rear end of the draft yoke, and a casting rigidly mounted between the sills at the rear of the draft yoke having a transverse bumping face to be engaged by the rear end of the yoke under

buffing stress, a central vertical web formed in said rear casting and supporting the bumping face, and horizontal flanges connecting each side of the vertical web with 5 the rear of the bumping face.

7. In a draft rigging for railway cars, the combination with spaced longitudinal car sills, of a coupler shank, a front stop mounted between the sills at their forward 10 ends, adapted for the reception of the coupler shank, a follower plate seating against the inner face of said front stop, a draft yoke connected with the coupler shank, a yielding pressure resisting member, interposed 15 between the follower plate and the rear end of the draft yoke, a rear stop casting rigidly mounted between the sills at the rear end of the draft yoke, and a carrier for the pressure resisting member running 20 lengthwise of the rigging, said carrier connected at its forward end to the bottom of the front stop and to its rear end at the rear stop casting.

8. In a draft rigging for railway cars, the 25 combination with spaced longitudinal car sills, of a coupler shank, a front stop mounted between the sills at their forward ends adapted for the reception of the coupler shank, a follower plate seating against the 30 inner face of said front stop, a draft yoke connected with the coupler shank, a yielding pressure resisting member interposed between the follower plate and rear end of the draft yoke, and a casting rigidly mounted 35 between the sills at the rear of the draft yoke having a transverse bumping face adapted to be engaged by the rear end of said yoke under buffing stress, a central vertical web formed in the casting and supporting 40 the bumping face and horizontal flanges connecting each side of the vertical web with the rear of the bumping face, said flanges tapering from their forward ends toward their rear ends, substantially as set 45 forth.

9. In a draft rigging for railway cars, the combination with spaced longitudinal car sills, of a coupler shaft, a front stop mounted 50 between the sills at their forward ends adapted for the reception of the coupler shank, a follower plate seated against the inner face of said front stop, a draft yoke connected with the coupler shank, a yielding pressure resisting member interposed be-

tween the follower plate and the rear end of 55 the draft yoke, and a casting rigidly mounted between the sills at the rear of the draft yoke having a transverse bumping face adapted to be engaged by the rear end of said yoke under buffing stress, a central longitudinal vertical web formed in the rear casting and supporting the bumping face, horizontal flanges connecting each side of the vertical web in rear of the bumping face, and transverse vertical webs supporting the 60 opposite sides of the longitudinal vertical web.

10. In a draft rigging for railway cars, the combination with spaced longitudinal car sills, of a coupler shank, a front stop 70 mounted between said sills at their forward ends, adapted for the reception of the coupler shank, a follower plate seating against the inner face of said front stop, a draft yoke connected with the coupler shank, a 75 yielding pressure resisting member interposed between the follower plate, and the rear end of the draft yoke and a casting rigidly mounted between the sills at the rear of the draft yoke having a transverse 80 bumping face adapted to be engaged by the rear end of said draft yoke under buffing stress, a central vertical web, and side vertical webs formed in the casting and supporting 85 the bumping face, horizontal flanges connecting each side of the vertical web, with the rear of the bumping face and a horizontal flange formed in each side web to strengthen the same.

11. In a draft rigging for railway cars, 90 the combination with spaced longitudinal car sills, of a coupler shank, a front stop mounted between said sills at their forward ends adapted for the reception of the coupler shank, a follower plate seating against 95 the rear face of said front stop, a draft yoke connected with the coupler shank, a rear stop casting tapering toward the rear end of the draft yoke and provided with a bumping face adapted to be engaged by 100 the rear end of said yoke, a yielding pressure resisting member including a barrel interposed between the follower plate and the rear end of the draft yoke, and a reinforcing member having tapering top and 105 bottom walls for the rear end of said barrel.

RICHARD D. GALLAGHER, JR.
